UNITED STATES PATENT OFFICE.

JOHN E. CADIGAN, OF NEW YORK, N. Y.

SAFETY ATTACHMENT FOR GAS-STOVES.

1,271,539.

Specification of Letters Patent.

Patented July 9, 1918.

Application filed September 5, 1917. Serial No. 189,840.

To all whom it may concern:

Be it known that I, JOHN E. CADIGAN, a citizen of the United States of America, residing at New York city, in the county of 5 New York and State of New York, have invented new and useful Improvements in Safety Attachments for Gas-Stoves, of which the following is a specification.

This invention relates to a safety attachment for gas stoves and has particular reference to a protecting guard which secures the valve in one of a number of its adjusted positions.

The main object sought to be accomplished by this invention is the provision of a device which retains the valves in a predetermined position and renders the accidental opening or closing of the same impossible.

Another object of the invention is the provision of a safety attachment which will minimize the danger of children tampering with the valves as the attachment offers a substantial barrier to the manipulation of the same as well as renders them fool-proof. A further object of the invention is the provision of a safety attachment of this class which is provided with an adjustable locking means for the handles of the valves whereby the attachment may be readily applied to any make of stove regardless of the distance between the valves.

A still further object of the invention is the provision of a device of the class described which is of simple construction, inexpensive to manufacture and thoroughly reliable and efficient for the purpose for which it is intended.

With these and other objects in view, the invention lies in the novel arrangement and combination of parts which are fully described in the following description particularly pointed out in the appended claims and shown in the annexed drawings, of which—

Figure 1 is a fragmentary plan view of a portion of a gas range.

Fig. 2 is a front elevation thereof.

Fig. 3 is a cross section on the line 3—3 of

Fig. 2, and

Fig. 4 is a sectional view on the line 4—4 of Fig. 1.

Referring to the drawings by characters of reference, A designates the feed pipe of a gas range which has leading therefrom to the burners the usual distributing pipes B,

in which are arranged the valves C. My attachment comprises a substantially curved plate 10, which is adapted to be clamped to the feedpipe A, by means of the split rings 11, which are here shown as formed from a portion of the plate 10. The rings 11, are provided with the ears 12, which receive a bolt 13, for the clamping of the plate 10, to the feed pipe. The longitudinal edges of the plate are bent upon themselves to form guide channels 14, which are adapted to receive the members 15, which are mounted for longitudinal sliding movement therein. The members 15, are provided with the upstanding lugs 16, between which are pivoted the arms 17, the latter being provided with a series of notches 18, which are adapted to engage the handles of the valves C. The retaining springs 19, are provided on the members 15, for engagement with the arms 17, in order to hold the arms in their adjusted positions. The notches 18, have communicating portions 20, which are intended for use on valve keys of the flat type. The members 15, being slidable on the plate 10, allow for variation in the distance between the valves whereby the device may be attached to any make of gas range.

In operation of the device the arm 17, has one of its notches normally engaged with the valve key whereby the same is held against casual or accidental movement. When the person desires to open or close the valve, the arm 17, is swung upwardly on its pivot and the key turned to the desired position. The arm is then swung downwardly and one of the notches is again engaged over the valve key to hold the same in its adjusted position. Any number of notches may be employed and it will be readily understood that a standard flow of gas will always be had by adjusting the valve key to a predetermined notch in the arm 17, which will greatly aid the user of the stove in securing similar adjustments of the flow.

While I have shown and described a simple and preferred form of accomplishing the purpose in view, I desire to have it understood that such alterations and changes that fall within the scope of the appended claims may be resorted to when desired.

What I claim is:

1. A valve guard for gas stoves comprising a plate adapted to be secured to the feed pipe of the valve, a member slidable on said

plate, an arm movably supported from said member and provided with a series of notches for interchangeably receiving the handle of the valve when said handle is in 5 respectively different positions and serving to hold the handle against movement, and means for holding said arm in a relatively fixed position.

2. An attachment for gas stoves comprising 10 a slidably mounted member adapted to be positioned adjacent to the valve, a swinging arm on said member, said member having a longitudinal series of notches for interchangeably receiving the handle of the

valve, and means on said member for holding the arm in a relatively fixed position. 15

3. An attachment for gas stoves comprising 20 a member adapted to be positioned adjacent to the valve, and a swinging arm on said member, said arm having a longitudinal series of notches arranged therein and opening onto one edge of the arm and adapted to interchangeably receive the handle of the valve to hold the same against movement. 25

In testimony whereof I affix my signature.

JOHN E. CADIGAN.
